GARMENT HANGER

Leonard A. Young, Detroit, Mich.

Application June 14, 1934, Serial No. 730,611

13 Claims. (Cl. 223—88)

The main objects of this invention are:

First, to provide an improved garment hanger having, by virtue of its shape and the materials with which it is constructed, means preventing 5 the creasing of the garments hung thereon and the contact therewith of metal parts.

Second, to provide a garment hanger which is not only simple in construction, but which is economical to manufacture and effective for the 10 purpose intended.

Third, to provide a garment hanger assembly which is capable of several adaptations.

Objects relating to details and economies of my invention will appear from the description to 15 follow. The invention is defined and pointed out in the claims.

Structures which are preferred embodiments of my invention are illustrated in the accompanying drawings, in which:

Fig. 1 is a view in front elevation of a garment hanger embodying the features of my invention.

Fig. 2 is a similar view showing the hanger partially formed, the assembly of the yoke and suspension hook being completed.

Fig. 3 is a perspective view of a shield for one of the arms of the yoke.

Fig. 4 is a perspective view of the strut or cross bar.

Fig. 5 is an enlarged fragmentary view partially broken away and shown in section to illustrate the connection between the strut and the yoke arm.

Fig. 6 is an enlarged transverse section of the yoke on a line corresponding to line 6—6 of Fig. 2.

Fig. 7 is an enlarged fragmentary view partially in section and partially in elevation showing the connection between the suspension hook and the yoke, the dotted lines showing an intermediate position of the hook.

Fig. 8 is a perspective view of the sheet metal blank used in forming the yoke after cutting, but before bending the same.

Fig. 9 is a view mainly in longitudinal section and partially in side elevation of a modification.

Fig. 10 is an enlarged transverse section on a line corresponding to line 10—10 of Fig. 9.

Fig. 11 is a fragmentary perspective view of a modification of the arm shield.

Fig. 12 is a fragmentary section on line 12—12 of Fig. 13, illustrating a modification of the connection between the strut and yoke arm.

Fig. 13 is a fragmentary bottom plan view, the sleeve being omitted for clearness.

Fig. 14 is a fragmentary plan view of a strip of sheet metal from which I cut the yoke blanks.

Fig. 15 is a view in front elevation of a partially formed garment hanger embodying a modification of the connection between the suspension 5 hook and yoke.

Fig. 16 is an enlarged fragmentary perspective view showing the first step of assembling the suspension hook with the yoke of the modification.

Fig. 17 is a similar view showing the suspension 10 hook swung to close its terminal loop, an operation or step which, although desirable, if inadvertently omitted will not affect the normal self-locking feature of the hook when swung to its upright position.

Fig. 18 is a similar view showing the suspension hook swung to its normal position with the parts in linking relation.

Fig. 19 is a view similar to Fig. 16, of a further modification showing the yoke provided with a 20 transverse central loop in its web.

Referring to Figs. 1 to 8, inclusive, of the drawings, 1 is a suspension hook, 2 is an arched yoke, and 3 is a strut or cross bar. I form the arched yoke 2 by suitably cutting and conforming the 25 sheet metal blank 4 to provide a downwardly facing channel section having a pair of spaced central openings 5, 5 in its web and a pair of cut-out inwardly extending opposed V-shaped or tapered tongues 6, 6 in its web spaced from the outer ends 30 of the downwardly divergent arms 7, 7 thereof.

For conventional commercial garment hangers, it is necessary that the yoke be sixteen inches from end to end, which necessarily requires a blank sixteen inches long. Sheet metal is readily 35 obtainable in strips having a maximum width of eleven inches, strips above eleven inches costing considerably more per pound than the standard eleven-inch stock. In order to use this less expensive standard stock, I cut the latter on the 40 bias, as illustrated by Fig. 14, the bias being such that the blanks cut therefrom are sixteen inches long when finished.

In Fig. 14, 22 is a strip of sheet metal eleven 45 inches wide, which is cut on the bias as at 23 to provide the blanks 4 for forming the yokes. The dotted lines 24 indicate subsequent cuts of the strip. This cutting of the blanks results in sharp points 25 at the ends of the blanks which I turn in as illustrated by Figs. 5, 13, and 12, to finish 50 the ends of the yoke. Thus, when the arms of the yoke are subsequently covered by the paper sleeves 10, there are no sharp points to protrude through the paper sleeve, and further, the ends 55 of the yoke are completely covered by the sleeves.

I cut the strip 22 on the bias to obtain a blank of the proper length without loss, the strip having a width less than such length. This is done by running the strip through the machine in the direction of its longitudinal axis, and by setting the forming and cutting dies on the bias. My method, in this respect, not only saves considerable money, but results in a yoke having finished ends, as pointed out above.

While I prefer to cut and conform the yoke in the same pressing operation, nevertheless I also contemplate cutting the blank, as shown in Fig. 8, in one operation and then conforming the blank in another operation. I also prefer to use sheet metal for the blank, although any desirable semi-rigid material may be used. The suspension hook 1 is preferably formed of wire, as shown, and has a shank 8 provided with a terminal loop 9 at its lower end engaging the yoke in the openings 5. This provides a very secure connection between these parts.

The hook is first formed with the terminal loop 9 open, so that the same can be threaded through the openings by manipulating the parts. The loop is thereupon closed by swinging the shank 8 to the position shown by the dotted lines of Fig. 7. After closing or locking the terminal loop 9 in this manner, the suspension hook is restored to its upright position. Thus, I provide a simple manual method of assembling the suspension hook and arched yoke.

When my suspension hook is put in place manually in this manner, it is simultaneously and permanently locked. The suspension hook may be said to be self-locking, and this is an essential feature of the present invention. I anticipate shipping the suspension hooks loose with the hangers, so that the cleaners may assemble them, because the hangers when assembled before shipment require a carton about double the size of that required when they are shipped unassembled. With my self-locking hook, the cleaner can readily assemble the yokes and suspension hooks. As pointed out above, such assembly requires no machinery. At the present, however, I prefer to assemble the hangers before shipment, although, as pointed out above, I contemplate shipping the hangers unassembled, thereby considerably reducing the size of the shipping carton.

50 In the modification illustrated by Figs. 15 to 18, inclusive, the terminal loop 26 of the suspension hook 1 is arranged in linking relation with the central loop 27 upstruck from the web of the yoke 2. The hook and yoke are assembled by positioning the parts, as illustrated by Fig. 16, by applying the terminal loop 26 to the web loop 27 by a lateral entering motion. The suspension hook is then swung to close the terminal loop, as shown by Fig. 17, after which the suspension hook is brought up straight to its normal position, as shown in Fig. 18. Thus, the loops are automatically locked in linking relation by simple manual movements. This method of assembling the suspension hooks with the yokes is extremely inexpensive, and when it is borne in mind that the widely used garment hangers sell for about one-half cent a piece, this is a very valuable feature. With this arrangement, the hooks can be very rapidly connected to the yokes, and locked at the same time.

In Fig. 19, I show a modification of the suspension hook and yoke connection, wherein the yoke 2 is provided with a transverse loop 28 punched upwardly therefrom for linking relation with the terminal loop 26 of the suspension hook 1.

The parts are assembled and locked by manipulations substantially similar to those described above in connection with Figs. 16 to 18, inclusive. In securing the hook in this embodiment, the end or bill of the terminal loop or open eye 26 is inserted through the loop on the hanger yoke or member, as shown in Fig. 16, and the shank of the hook pushed or bent over, as shown in Fig. 17, which closes the loop or eye and the hook can then be swung to the upright position, as shown in Fig. 18.

In the past, the suspension hooks and yokes have been connected by wrapping the suspension hook shank around the yoke, and by machine operations and the like. My invention requires 15 the use of considerably less material than the prior structures, and further, the cost of labor is reduced in my method of assembly. I apply and lock the suspension hook to the yoke in one operation, without the use of a machine—whether 20 this is done with perforations, as shown in Fig. 7, or whether it is done with loops pressed out of the yoke, through which the suspension hook is linked, as shown in Fig. 15. This feature results 25 in a very fast production with correspondingly low cost.

On the arms of the yoke, I slip tubular shields 10, 10 preferably of paper. The tubular strut 3 is arranged with its ends engaging the tongues 6. The strut is preferably a cylindrical paper tube, 30 as shown in Figs. 1, 4, and 5. The ends of the strut are suitably beveled at 12 and are securely held in place by the tongues 6, the strut acting to hold the shields 10 in place on the arms.

In assembling the yoke and strut, the tongue 35 is forced through the paper shield, thereby making a tight and snug fit, with no metal exposed at the point of connection. The sleeves are preferably paper tubes about one-half to five-eighths of an inch in diameter, and are slid over the 40 yoke from either end, the two sleeves meeting at the shank of the suspension hook. At the time of applying the strut, the tongues 6 are forced through the paper sleeves.

By forcing the tongues through the paper 45 sleeves, the latter are simultaneously and automatically locked in position. Not only does the strut fill the capacity of a trouser support and a supporting element for the yoke, but it also serves as a locking device in holding the paper sleeves 50 in place. This is a very essential feature, because it would be possible for the sleeves to come off were they not anchored or locked in position. In assembling the parts, the yoke is sprung outwardly or flattened, and reacts to engage the ends 55 of the strut and hold the parts in assembled relation, the length of the strut being such that this result is obtained. The paper sleeve is clamped between the end of the strut and the yoke, so that it is held firmly and cannot slide up and 60 down; and this, coupled with the piercing of the sleeve by the tongue, provides a double locking action.

In Fig. 11, I show a modification of the tubular shield, the tube 13 consisting of a strip, preferably 65 of paper, folded on itself, the edges being connected at 14 by glue or other suitable means.

In Fig. 12, I show a modification of the connection between the end of the strut and the yoke arm, wherein the tongue 6 extends within 70 the end of the tubular strut 3 as shown. In some respects, this provides a better connection than that shown in Fig. 5. The inwardly projecting tongues are preferably tapered or of V shape, the width of the tongue at the base being such that 75

it expands the tubular strut at its ends, so that the strut is flattened, as shown. In this way, it is impossible for the strut to turn on the tongues, and allow the trousers to fall off, like a towel off a roller. My arrangement holds the strut firmly, so that it will not roll or revolve on the tongues. By widening the tongue at its base and by making it of V shape, it readily enters the end of the tubular strut, and secures the latter in position without any possibility of revolving.

In this case, when the strut is assembled with the yoke, the tongues are forced through the paper sleeves, the tongues entering the hollow ends of the paper tube or strut. This locks the parts, and provides a finished product with all metal parts covered. Thus, the sleeves are held in place not only by the tongues, but also by being clamped between the yoke and the ends of the strut—the tongue piercing the sleeve before it enters the strut.

In the modification of my invention illustrated by Figs. 9 and 10, 29 is an arched sheet metal yoke of downwardly facing curved cross section having a pair of spaced central openings 15, 15 and a pair of inwardly extending cut-out tongues 16, 16 spaced from the outer ends of its downwardly divergent arms 17, 17. 18 is a wire suspension hook having a shank 19 provided with a terminal loop 20 at its lower end engaging the yoke in the openings 15.

Between the tongues 16, I arrange a sheet metal strut 21 of downwardly facing curved cross section, the ends of the strut being clamped between the inner face of the yoke and the tongues. The width of the strut is preferably less than that of the yoke, to provide a secure connection between the parts. If desired, the yoke and strut may be made of any suitable semi-rigid material. The strut can well be made of suitably shaped paper board or the like.

From the above description of my invention, it will be apparent to those skilled in the art that I provide a clothes hanger of improved construction, and one which can be economically manufactured and readily assembled by even an inexperienced person. When once assembled, the resiliency of the yoke insures a secure connection between the parts even in use and where relatively heavy garments are hung on the device. The garments are protected from creasing by the rounded shape of the parts, and further, the garments are protected from contact with any metal parts in my preferred construction.

With the parts thus arranged, the hanger has a wide range of uses and adaptations. Sometimes it is not necessary to provide the hanger with a cross strut or bar or to cover the arms of the hanger, and in that case both the tubular shields 10 and the cross bar are omitted, the hanger being used in the condition shown in Fig. 2. For other uses it is not deemed necessary to cover the arms, and the tubular cross bar 3 is employed, this cross bar providing a suitable surface to prevent creasing of garments such as trousers folded over the same and also to prevent or minimize creeping of the garments thereon. This avoids the necessity for using paper or cardboard coverings for cross bars as is now frequently done with wire hangers.

Where desired, the coverings for the arms of the hanger or yoke may be used as illustrated in Fig. 1, thus providing a completely paper-surfaced hanger at a very nominal cost. All of these adaptations may be made by the user, that is, by

the cleaner, dyer, or laundryman, so in practice very substantial economy results.

Where the loops are pressed upward from the channel yoke, and through which loops the terminal loops of the suspension hooks are linked and brought up straight and locked, as in Fig. 15, a simpler assembly is provided than where two holes are provided in the web of the yoke, as in Fig. 7. In the modification, the locking of the suspension hooks is assured by the use of the garment hanger, it being necessary only to enter the terminal loop with the web loop. In Fig. 7, the locking of the suspension hook with the yoke requires a manual operation which is not supplied by the ordinary use to which the hanger is put. Thus, where the hangers are shipped unassembled, I prefer to use the construction illustrated by Figs. 15 to 18, inclusive, or the construction illustrated by Fig. 19.

I have illustrated and described my improvements in embodiments which I have found very practical. I have not attempted to illustrate or describe other embodiments or adaptations, as it is believed this disclosure will enable those skilled in the art to embody or adapt my improvements as may be desired.

Having thus described my invention, what I claim as new and desire to secure by Letters Patent is:

1. A garment hanger comprising an arched sheet metal yoke of downwardly facing channel section having a pair of spaced central openings in its web and a pair of cut-out inwardly extending opposed tapered tongues in its web spaced from the outer ends of the downwardly divergent arms thereof, a wire suspension hook having a shank provided with a terminal loop at its lower end engaging said yoke in said openings, tubular paper shields on the arms of said yoke, and a tubular paper strut piercing said shields and engaging said tongues at its ends so that the latter are flattened.

2. A garment hanger comprising an arched yoke of downwardly facing channel section having a pair of spaced central openings in its web and a pair of cut-out inwardly extending opposed tongues in its web spaced from the outer ends of the downwardly divergent arms thereof, a suspension hook having a shank provided with a terminal loop at its lower end engaging said yoke in said openings, tubular shields on the arms of said yoke, and a tubular strut engaging said shields and tongues at its ends.

3. A garment hanger comprising an arched yoke of downwardly facing channel section having a pair of cut-out inwardly extending opposed tapered tongues in its web spaced from the outer ends of the downwardly divergent arms thereof, a suspension hook having a shank provided with a terminal loop at its lower end engaging said yoke, tubular shields on the arms of said yoke, and a tubular strut engaging said shields and tongues at its ends.

4. A garment hanger comprising an arched yoke having a pair of spaced central openings, and a suspension hook having a shank provided with a terminal loop at its lower end engaging said yoke in said openings.

5. A garment hanger comprising an arched sheet metal yoke of downwardly facing channel section having a pair of inwardly extending opposed tongues in its web spaced from the outer ends of the downwardly divergent arms thereof, paper shields on the arms of said yoke, and a strut

- extending into said shields and engaging said tongues at its ends.
6. A garment hanger comprising an arched yoke of downwardly facing curved cross section having a pair of spaced central openings and a pair of inwardly extending cut-out tongues spaced from the outer ends of its downwardly divergent arms, a suspension hook having a shank provided with a terminal loop at its lower end engaging said yoke in said openings, and a strut of downwardly facing curved cross section engaging said tongues at its ends, the width of said strut being less than that of said yoke.
7. A garment hanger comprising an arched yoke of downwardly facing curved cross section having a central upstruck loop, and a suspension hook having a shank provided with a terminal loop at its lower end engaging said yoke loop.
8. A garment hanger comprising an arched yoke of downwardly facing channel section having inturned tapered tongues spaced from the ends of its downwardly divergent arms, shields sleeved on the arms, and a tubular strut having its ends beveled to fit the web of the yoke channel, the strut being engaged by said tongues in clamped relation with said web, the sides of the strut also fitting between the flanges of said yoke channel, the tongues extending within the ends of the tubular strut and flattening the same.
9. A garment hanger comprising an arched yoke of downwardly facing channel section having inturned cut-out tongues spaced from the ends of its downwardly divergent arms, shields sleeved on the arms, and a tubular strut having its ends beveled to fit the web of the yoke channel, the strut extending through the shields and being engaged by said tongues in clamped relation with said web and the shields, the sides of the strut also fitting between the flanges of said yoke channel.
10. A garment hanger comprising an arched yoke of downwardly facing channel section having inturned V-shaped tongues at the ends of its downwardly divergent arms, and a tubular strut having its ends beveled to fit the web of the yoke channel, the strut being engaged by said tongues in clamped relation with said web, the sides of

the strut also fitting between the flanges of said yoke channel, the tongues extending within the ends of the tubular strut and frictionally engaging the same to prevent the strut from turning on the tongues.

11. In a garment hanger, the combination of an arched yoke of downwardly facing channel section having opposed inturned V-shaped tongues in its arms, a suspension hook secured to the center of said yoke, paper sleeves on said arms, and a cylindrical paper strut engaging said tongues at its ends, the tongues piercing said sleeves and projecting within the ends of said strut to flatten and prevent rotation of the strut, the sleeves being clamped between the arms and the ends of the strut whereby they are locked in position and completely cover the arms, the length of said strut being such that the yoke is sprung slightly thereby and reacts to engage firmly the ends of the strut and hold the parts in fixed relation as assembled.

12. In a garment hanger, the combination of an arched yoke having opposed inturned V-shaped tongues in its arms, paper sleeves on said arms, and a cylindrical strut engaging said tongues at its ends, the tongues piercing said sleeves and projecting within the ends of said strut to flatten and prevent rotation of the strut, the sleeves being clamped between the arms and the ends of the strut whereby they are locked in position, the length of said strut being such that the yoke is sprung slightly thereby and reacts to engage firmly the ends of the strut and hold the parts in fixed relation as assembled.

13. In a garment hanger, the combination of an arched yoke having opposed inturned tongues in its arms, paper sleeves on said arms, and a cylindrical strut engaging said tongues at its ends, the tongues piercing said sleeves and coacting with the yoke to flatten and prevent rotation of the strut, the sleeves being clamped between the arms and the ends of the strut whereby they are locked in position, the length of said strut being such that the yoke is sprung slightly thereby and reacts to engage firmly the ends of the strut and hold the parts in fixed relation as assembled.

LEONARD A. YOUNG.
